UNITED STATES PATENT OFFICE.

CLAUDE A. P. TURNER, OF MINNEAPOLIS, MINNESOTA.

REINFORCED-CONCRETE BEAM.

No. 927,194.

Specification of Letters Patent.

Patented July 6, 1909.

Application filed June 5, 1907. Serial No. 377,845.

To all whom it may concern:

Be it known that I, CLAUDE A. P. TURNER, of Minneapolis, county of Hennepin, State of Minnesota, have invented new and useful Improvements in Reinforced - Concrete Beams, and do hereby declare that the following is a full, clear, and exact description thereof, reference being had to the accompanying drawing, in which—

10 Figure 1 is a vertical longitudinal section of a reinforced concrete beam embodying my invention and portions of columns supporting the same; Fig. 2 a horizontal section on the line 2—2 of Fig. 1; Figs. 3, 4 and 5 are, respectively, cross sections on the lines 3—3, 4—4 and 5—5 of Fig. 1; and Fig. 6 detail views of portions of the reinforcing rods.

15 The object of my invention is to so reinforce concrete beams as to provide for taking care of all the strains or stresses to which the same are subjected, by an arrangement of rods which will reduce the cost of construction without any sacrifice of strength, and to this end—

20 My invention consists in the reinforced concrete beam constructed substantially as hereinafter specified and claimed.

25 In concrete beam construction, there must be taken into account the bending moments, the shearing stresses, and the tensile strains, in providing the beam with adequate reinforcing means, and in making my invention I have had in view such reinforcement as will take care of these stresses.

30 The beam, A, shown in the drawing is of ordinary construction, being formed in molds in the usual manner, and extends over columns or supports B. Extending longitudinally through the beam near its bottom is a series of straight, horizontal steel rods C to take the tensile strains, and in addition to this series of rods, there are two other series of steel rods D and E, respectively, which, speaking generally, also extend longitudinally through the beam, not only between the adjacent columns B, but to a point beyond the same, and the rods of each of these two series D and E incline from a point near the bottom of the beam and a point in about the same plane as the plane of the rods C, upward, to a point at or near the top of the beam and above the beam-supporting column, from which point the rods incline downward into the portion of the beam on the opposite side of said support, and the rods terminate in hooks to firmly anchor

them in the concrete. It will be observed that there is a double inclination of the rods through the beam on opposite sides of the supporting column, and that the rods are continuous or uninterrupted at this point, and as the maximum strains occur at this point, and the greatest resisting moments are needed at this point, it will be seen that the structure is amply able to withstand the tensile strains and the bending moments of the beam, and that by reason of the downward inclination of the rods from the supporting columns, the rods provide against the shearing stresses, (which are greatest adjacent the columns), since the vertical component of the tension in shear is carried directly by the rods because of their inclination.

35 The angles of inclination of the two sets or series of rods D and E is not the same. In the case of the rods D their direction downward is toward the point of contra-flexure of the beam, where, for a uniform load, the moment is zero, and from such point the rod extends horizontally to the point of contra-flexure near the next supporting column. In the case of the rods E of the other series they are inclined from a point above the supporting column to a point at or near the longitudinal center of the beam, so that the rods of this series extend in a zig-zag course through the beams, forming obtuse angles whose apexes are successively at or near the bottom of the beam at a point midway between the supporting column and above the columns, and this arrangement of the rods is to provide for cases where the load upon the beam is not uniform. It will be observed that in the cases of both sets of the rods with inclined portions, and especially in view of the fact that such rods are carried across and beyond the supporting columns, the tensile strains produced by loads upon the beam will be sustained by the inclined portions of the rods. The horizontal portions of the rods D, of course, assist in sustaining the tensile strains to which the beam is subjected. It will be noted, too, that the rods lap by each other through the beam above the supports, so that there is a doubling of the section of the bars at this point, which, of course, adds greatly to the strength of the structure, and adds this strength at a point where it is needed, because of the strains upon it thereat.

40 An important advantage from my arrange-

ment of the rods is that the centering may be removed at an early period in the work of construction, with perfect safety.

Having thus described my invention, what

5 I claim is:

1. The combination of columns, concrete beams extending from column to column, rods extending through the beams above and to opposite sides of the columns, the rods 10 from one sidelapping past those from the other side, and said rods being bent to incline downward into the beams in opposite directions, the apex of the bend being at a point substantially midway of the column 15 from side to side thereof.

2. The combination of columns, concrete beams extending from column to column, rods extending through the beams above and to opposite sides of the columns, the rods 20 from one sidelapping past those from the other side, and said rods being bent to incline downward into the beam in opposite directions, the apex of the bend being at a point substantially midway of the column 25 from side to side thereof, different rods being

inclined at different angles and their lowest points being situated at different distances in the beam from column to column.

3. The combination of columns, concrete beams extending from column to column, rods extending through the beams above and to opposite sides of the columns, the rods from one sidelapping past those from the other side, and said rods being bent to incline downward into the beams in opposite 35 directions, the apex of the bend being at a point substantially midway of the column from side to side thereof, different rods being inclined at different angles and their lowest points being situated at different distances in the beam from column to column, and rods running horizontally through the beam near the bottom thereof. 40

In testimony that I claim the foregoing I have hereunto set my hand.

CLAUDE A. P. TURNER.
